INVENTOR,

by
Attorney.

UNITED STATES PATENT OFFICE.

BRUNO ASCHENBACH, OF ST. JOSEPH, MISSOURI, ASSIGNOR OF ONE-HALF TO
GEORGE L. HERMAN MUEHE, OF SAME PLACE.

WINDOW.

SPECIFICATION forming part of Letters Patent No. 400,427, dated April 2, 1889.

Application filed October 25, 1888. Serial No. 289,132. (No model.)

To all whom it may concern:

Be it known that I, BRUNO ASCHENBACH, a citizen of the United States of America, residing at St. Joseph, in the county of Buchanan and State of Missouri, have invented certain new and useful Improvements in Windows; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to certain new and useful improvements in window-frames and sash; and it consists in the novel construction and combination of the parts thereof, as will be more fully hereinafter described and claimed.

The object of my invention is to provide a convenient form of frame and sash, wherein the sash may be readily removed, and attachments whereby the sashes are adapted to be held in a raised or lowered position. I attain this object by the construction illustrated in the accompanying drawings, wherein like letters of reference indicate similar parts in the several views, and in which—

Figure 1 is a front elevation of a window-frame and sash, partially broken away. Fig. 2 is a transverse vertical section on the line $x-x$ of Fig. 1. Fig. 3 is a horizontal section on the line $y-y$ of Fig. 1. Fig. 4 is a detail perspective view of a part of one of the guide-strips adapted to be centrally fitted in one of the jambs. Fig. 5 is a detail perspective view of a part of one of the window-frames.

A indicates the window-frame, and B and B' the lower and upper sash. The inner opposing faces of the jambs of the frame A are formed with vertical slots a and a' , extending throughout their whole length. Within these slots a and a' sash-guides A' and A² are fitted, one on each side of the frame, and are of such dimensions as to allow movement forward and back within their respective slots. The said guides A and A' are formed with channels or grooves b and b' in the outer and inner faces thereof. The jambs are made hollow, and at

the upper and lower parts thereof flat springs S are secured. These springs S are secured at one of their ends to said jamb-frame, as shown, and the free ends thereof project outward and in reverse directions, and engage 55 and operate within the grooves or channels b' of the guides adjacent thereto.

By the construction above set forth it will be seen that both strips or guides A' and A² are thrust forward or outward by the springs 60 and held snugly against the vertical sides of the sash, but are adapted to be pressed inward against the springs S, to thereby readily remove the sash. To prevent the guide-strips A' and A² from being pressed outwardly too 65 far and cause a binding of the sash, pins are secured thereto, which bear against the stationary part of the jambs. To lock the guides A' and A² in a fixed position, pins p and p' are employed, which may be ornamented and in 70 the form of curtain-holders. These pins are used at the lower and upper parts of the jambs, passing through apertures in the front sides of the jambs, and into one of the two parallel apertures s' and s^2 in the guides A' and A² at 75 the upper and lower parts thereof. When said pins are in engagement with the apertures s^2 , the guides are locked in their normal positions, as shown in Fig. 1, and when the said guides are pressed inward the said pins 80 are passed through the apertures s' , thus locking the said guides back in the jambs with their flanges b^3 flush with the faces of said jambs, thus releasing the sash and permitting of its removal. 85

The stiles of the sash B and B' are grooved and ride each on one of the flanges b^3 of the channels or grooves b of the guides A' and A². The said sashes are arranged as in the usual manner, one back of the other, to allow them 90 to slide past each other. The one guide A' has the lower part of the inner flange, b^3 , and the upper part of the outer flange, b^3 , evenly corrugated, as at b^2 , Fig. 1, and the adjacent stile of the lower sash, B, is recessed, as at b^4 . 95 Within said recess b^4 a depending spring-arm, C, is secured, whose lower end, c , is enlarged and rounded to engage the corrugated surface b^2 . The upper sash, B', is provided with a similar arm, C, arranged in the reverse direc- 100

tion, and in like manner engages with a corrugated surface on the outer flange, b^3 . By means of the construction above set forth the sash may be held in a raised or lowered position, 5 the spring-arms c binding with sufficient force on the corrugated surfaces to sustain the weight of the sash, but offering small resistance when the sashes are closed.

By my improved construction the sash-retaining strips commonly secured to the jambs adjacent to the sash are dispensed with, as 10 well as suspending cords, pulleys, and weights, the said sash being adapted to be readily removed when desired, thus providing a convenient frame and sash.

I claim—

1. The combination, substantially as described, of a window-frame the sides of which are provided each with a slot, spring-pressed 15 guide-strips loosely seated therein and hav-

ing a central groove or channel in their outer faces to form inner and outer flanges, and the upper and lower sash having grooved stiles engaging, respectively, the outer and inner flanges of the guide-strips.

2. In a window, the combination of the slotted jambs having movable grooved or channeled guide-strips therein, having transverse apertures s' and s^2 , the springs in rear of and engaging said guides, the pins s , the pins p and p' , and the sash having grooved stiles 25 sliding on the flanges of the channels or grooves in the guides, substantially as described.

In testimony whereof I have affixed my signature in presence of two witnesses.

BRUNO ASCHENBACH.
